UNITED STATES PATENT OFFICE.

GEORGE W. CAMERON, OF HONDO, TEXAS.

PRESS.

1,188,894.

Specification of Letters Patent. Patented June 27, 1916.

Application filed September 13, 1915. Serial No. 50,492.

To all whom it may concern:

Be it known that I, GEORGE W. CAMERON, a citizen of the United States, residing at Hondo, in the county of Medina and State of Texas, have invented certain new and useful Improvements in Presses, of which the following is a specification, reference being had to the accompanying drawings.

This invention relates to certain improvements in presses and has relation more particularly to a device of this general character especially designed and adapted for use in packing cotton; and it is an object of the invention to provide a press having novel and improved means whereby a plunger or ram may be reciprocated relative to the packing box.

Furthermore, it is an object of the invention to provide a press having novel and improved feeding means whereby the material, such as cotton, to be packed is automatically delivered within the packing chamber during a predetermined period of the travel of the ram or plunger.

The invention also has for its object to provide a press including a movable plunger or ram and a feeding mechanism and having novel and improved means whereby the operation of the feeding mechanism is under control of the plunger or ram whereby said feeding mechanism is caused to operate intermittently.

A still further object of the invention is to provide a device of this general character having novel and improved means whereby the movable parts thereof are effectively maintained against movement upon disconnecting the device from its source of power.

The invention consists in the details of construction and in the combination and arrangement of the several parts of my improved press whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a view in side elevation illustrating an embodiment of my invention, the structure coacting therewith being shown in fragment; Fig. 2 is an enlarged sectional

view taken substantially on the line 2—2 of Fig. 1, with a coacting compressor shown in fragment; Fig. 3 is a vertical longitudinal sectional view taken through the device as disclosed in Fig. 2; Fig. 4 is a fragmentary detail sectional view of the feeder controlling mechanism, the parts in elevation being at the side opposite to that shown in Fig. 3; Fig. 5 is a sectional view taken substantially on the line 5—5 of Fig. 1; Fig. 6 is a sectional view taken substantially on the line 6—6 of Fig. 5; Fig. 7 is a sectional view taken substantially on the line 7—7 of Fig. 5; Fig. 8 is a sectional view taken substantially on the line 8—8 of Fig. 1; and Fig. 9 is an enlarged longitudinal sectional view taken through the hopper and the feeding mechanism positioned therein.

As disclosed in the accompanying drawings, A denotes a fragment of a compressor structure of a well known form and a detail of which forms no part of the present invention, and said compressor A includes the well known boxes B affording the packing chambers.

Extending longitudinally from and operatively supported by the upper sills S of the compressor A are the spaced parallel beams 1, the outer extremities of which being operatively engaged with and supported by the standard 2, said beams 1 serving as a support for my invention as herein embodied. Extending upwardly from each of the beams 1 and spaced longitudinally thereof are the posts 3, the posts of one beam being transversely aligned with the posts of the second beam and the upper extremities of the posts of each of the beams 1 are tied or connected by the horizontally disposed bar 4, the extremities of which extend beyond the posts 3. Adjacent end portions of the bars 4 have engaged therewith the transversely disposed members 5 arranged in parallelism and to the under surfaces of which are secured the longitudinally aligned bearings 6 in which are rotatably supported the idle shafts 7, the inner extremities of which terminating in a plane substantially flush with the outer faces of the posts 3 and the inner extremities of said idle shafts have affixed thereto the sprocket wheels 8 around each of which is disposed the chain 9 also directed around a sprocket 10 positioned a predetermined distance below the sprocket 7 and in vertical alinement therewith. The sprocket 10 is affixed to the inner extremi-

ties of the short shafts 11 rotatably mounted in the bearings 12 secured to the upper surfaces of the parallel members 14 supported by and disposed transversely of the beams 1 adjacent their opposite extremities and outwardly disposed relative to the posts 3, the members 14 adjacent the inner end of the beam 1 being extended beyond one of said beams, as indicated at 15, and for a purpose 5 pose to be hereinafter referred to.

16 denotes a plunger head or ram provided adjacent its opposite ends with the upstanding transversely disposed flanges 17 which are pivotally engaged with the lower 10 extremities of the rods or pitmen 18, the upper extremities of said rods or pitmen 18 being in pivotal engagement with the horizontal bar 19. The ends of the bar 19 are rotatably engaged with the chains 9 wherever 15 by it will be perceived that reciprocable movement will be imparted to the plunger or ram 16 upon the travel of the chains 9. Furthermore, it is to be particularly noted in Figs. 2 and 5 that the pivotal connections 20 between the rods or pitmen 18 and the flanges 17 are offset transversely relative to the positions of the shafts 7 and 11 so that upon downward travel of the rods or pitmen 18 a direct vertical thrust will be imposed 25 upon the head or ram 16.

The opposed faces of the posts 3 are provided with the vertical guide-ways 20 substantially U-shape in cross section and having their opposite extremities overlying the 30 opposed faces of the beams 1 and the bars 4.

As herein embodied, the flanges 17 are comprised in the substantially rectangular frames 21 extending upwardly from the head or ram 16 and having the vertical bars 22 thereof positioned within the guide-ways 20 whereby travel of the head or ram 16 in a fixed vertical path is assured. In order to assure requisite strength for each of the frames 21, I find it of advantage to have 45 the vertical bars 22 connected by the crossed struts or braces 23.

Each of the shafts 11 has affixed thereto, a gear wheel 25 in mesh with a small gear 26 fixed to the shaft 27 disposed longitudinally 50 of one of the beams 1 and rotatably supported by the bearings 28 secured to the upper surfaces of the members 14. One extremity of the shaft 27 is provided with a gear 79 of a predetermined size in excess of the 55 gears 26 and said gear 79 is in mesh with a smaller gear 29 fixed to the shaft 30 mounted in the bearings 31 secured to the upper surfaces of the extended portions 15 of the inner bars 14, as hereinbefore referred to.

60 One extremity of the shaft 31 is provided with the fast pulley 32 and the loose pulley 33 with which is adapted to coat the driving belt 34 leading from a suitable source of power and as generally indicated by the 65 drive shaft 30.

The means for shifting the belt 34 relative to the pulleys 32 and 33 as herein embodied, comprises the member 35 disposed at the outer face of the front beam 1 and having its forward extremity disposed 70 through the guide 36 carried by the beam 1, while the opposite or inner extremity of the member 35 is supported by the link 38 pivotally engaged with the member 35 and with the beam 1. The outer extremity of the 75 member 35 is provided with the upstanding arms 37 coacting with the belt 34 in a conventional manner.

40 denotes a lever pivotally engaged with the beam 1 above the member 35 and operatively engaged with the rear extremity of the member 35 through the medium of the rod 41 also pivotally engaged with the lever 40.

In practice, I find it of advantage to provide means whereby the ram or head 16 and the other movable parts of my improved device are positively locked against movement when the belt 34 is engaged with the loose pulley 33 and for this purpose I provide the 80 shaft 30 with the band wheel 42 with which coacts the band 43, one extremity of the band being secured to the forward beam 1 and the opposite extremity secured to the crank shaft 44. The shaft 44 is provided 85 with a rock arm 45 overlying the member 35 and adapted to be engaged by the upstanding projection 46 carried by the member 35 whereby it will be perceived that as the member 35 is moved to shift the belt 34 90 from the fixed pulley 32 to the loose pulley 33, the rock arm 45 will be engaged by the projection or extension 46 to impart sufficient axial rotation to the crank shaft 44 as to cause the band 43 to frictionally engage 100 the band wheel 42 and thus effectively brake the device.

The rear beam 1 is provided with the longitudinally spaced vertical uprights 47 with which is engaged the hopper 48 adapted to discharge within a box B when operatively positioned below the head or ram 16 and the material, such as cotton, is adapted to be delivered directly within the hopper 48 from the condenser C, as is particularly shown in Fig. 2. The discharge of the cotton or other material within a box B, during the period that the plunger or head 16 is within the box, is under control of the gate 49 carried by the longitudinal 110 marginal portion of the head or ram 16 adjacent the hopper and as is particularly disclosed in Fig. 5, it will be noted that the gate 49 is connected with the ram or head 16 by the resilient members 50 which permit the gate 49 to assume a vertical position as the head or ram enters the box B so that said gate will offer no obstruction to the travel of the head or ram 16. I also find it desirable to provide the lower marginal 120

position of the box 30 with the longitudinally pivoted member 31. I also find it of advantage to provide a means whereby the return or idle material within the hopper 48 will be progressively discharged within a box 33 and, as herein embodied, I dispose longitudinally of the hopper 48 adjacent its lower end the fixed track 32 with which is rotatably engaged the hollow member 33 preferable triangular in cross section and one end of said member 33 is provided with a slope 34 extending rearwardly of the hopper 48 through an angle thereof and provided with a corner 35 beneath the member 33 and disposed 36 at an angle 36 to the longitudinal axis of the member 33 so that the track 32 is longitudinally rotatably relative to the axial center of the member 33 and thereby engaged therewith the lower extremities of the fingers 55 which extend 37 through suitable openings in the sides of the member 33 and upon rotation of said member 33 are adapted to extend exteriorly thereof and engage the bottom of either material within the hopper 48 and thus progressively 38 empty same for same to be discharged within the box 33. It will also be understood that at the dogs 56 of the track 32 the track 32 is rotatable with the member 33. It is also to be observed that the track 32 is disposed in a 39 direction away from the discharging face of the hopper 48 so that the cotton or other material will be stripped from the fingers 55 by the time said fingers have reached the point of discharge.

40 The sprayer 39 has disposed therewith the chain 40 which extends upwardly and around the sprocket 41 fixed to the stub shaft 48 operatively supported by one of the uprights 47 and the standard 59 projecting 41 upwardly from the adjacent or outer beam 1. The shaft 48 has applied thereto the fixed pulley 60 and the loose pulley 61 with which is adapted to coat the belt 62 leading from a suitable source of power, said 42 power being herein disclosed as the drive shaft 80. The standard 59 is provided with a laterally disposed arm 63 through the outer extremity of which is loosely disposed the elongated member 64 having disposed therefrom intermediate its length the fingers 65 between which is disposed the belt 62 and whereby said belt may be shifted from one of the pulleys 60 or 61 to the other. The belt 62 is normally maintained 43 operatively engaged with the loose pulley 61 through the medium of the expandable member 66 herein disclosed as a conventional coil spring surrounding the member 64 and interposed between the arm 63 and a stop 67 adjustably engaged with the outer extremity of the member 64. It will be apparent that by adjusting the stop 67 longitudinally of the member 64, the tension of the expandable member 66 may be varied as 44 the requirements of practice may demand.

45 The inner extremity of the member 64 has pivotally engaged therewith the rock arm 68 carried by the shaft 69, herein disclosed as rotatably supported by and disposed transversely through the rear beam 70. The inner extremity of the shaft 69 is provided with the depending rock arm 70 having pivotally engaged with the free extremity thereof the link 71 also pivotally engaged with the upstanding arm 72 of the bell lever 73, said bell lever having its heel portion pivotally supported between the main frame and the box 33.

46 The front portion of the substantially horizontal arm 74 of the bell lever 73 is provided with the lateral extension 75 adapted to be engaged by the outer extremity 76 of the upstanding arm 71 carried by the head or arm 68 whereby it will be perceived that upon the upward travel of the head or arm 68 reaching a predetermined point, the bell lever 73 will be tripped sufficiently as to cause the belt 62 to be shifted from the loose pulley 61 to the fixed pulley 60 so that the feeding mechanism will be caused to 47 operate and the belt 62 is maintained in operative engagement with the fixed pulley 60 through the medium of the vertical edge 78 of the arm 68. It will also be perceived that after the head or arm 68 has completed its ascent and has descended sufficiently to disengage the arm 71 from the lateral projection 75 of the bell lever 73, the expandable member 66 will automatically shift the belt 62 from the fixed pulley 60 to the idle pulley 61 so that the feeding mechanism will be idle or inoperative during the period when the arm or head 68 is disposed within a box 33.

48 From the foregoing description, it is 49 thought to be obvious that a press constructed in accordance with my invention is particularly well adapted for use by reason of the convenience and facility with which it may be assembled. 50

I claim:

51 1. A device of the character described comprising a reciprocating plunger, a hopper delivering in advance of the thrust of the plunger, and a gate carried by the plunger for controlling the discharge from the hopper, said gate being resiliently connected at its lower end with the plunger, said resilient connection permitting a movement of the gate independently of the plunger. 52

53 2. A device of the character described comprising a reciprocating plunger, means for operating said plunger, means for rendering said operating means inoperative, and a braking means for the plunger operable under the influence of the last named means. 54

55 3. A device of the character described comprising a reciprocating plunger, means for operating said plunger, means for rendering

dering said operating means inoperative, and a braking means for the plunger operable under the influence of the last named means, both of said last named means being 5 operable in unison.

4. A device of the character described comprising a plunger, a hopper discharging in advance of the plunger, a feeding mechanism within the hopper, said mechanism 10 comprising a stationary crank member disposed through the hopper, a hollow body rotatably supported within the hopper and disposed around the crank, said crank being offset relative to the axial center of the hollow member, fingers loosely engaged with 15 the crank and disposed through the hollow member, and means for rotating said hollow member.

5. A device of the character described 20 comprising a plunger, a hopper discharging in advance of the plunger, a feeding mechanism within the hopper, said mechanism, comprising a stationary crank member disposed through the hopper, a hollow body 25 rotatably supported within the hopper and disposed around the crank, said crank being offset relative to the axial center of the hollow member, fingers loosely engaged with the crank and disposed through the hollow 30 member, and means for rotating said hollow member, said hollow member being angular in cross section.

6. A device of the character described 35 comprising a plunger, a hopper discharging in advance of the plunger, a feeding mechanism within the hopper, said mechanism comprising a stationary crank member disposed through the hopper, a hollow body 40 rotatably supported within the hopper and disposed around the crank, said crank being offset relative to the axial center of the hol-

low member, fingers loosely engaged with the crank and disposed through the hollow member, and means for rotating said hollow member, said hollow member being triangular in cross section. 45

7. A device of the character described comprising a reciprocating plunger, a rotatable feeding member delivering in advance of the thrust of the plunger, a source 50 of power, a fixed pulley carried by the feeding member, an idle pulley carried by the feeding member, a belt coacting with the pulleys and the source of power, means for normally maintaining the belt in engagement with the idle pulley, and means carried by the plunger coacting with said last named means for throwing the belt in engagement with the fixed pulley. 55

8. A device of the character described 60 comprising a reciprocating plunger, a rotatable feeding member delivering in advance of the thrust of the plunger, a source of power, a fixed pulley carried by the feeding member, an idle pulley carried by the feeding member, a belt coacting with the pulleys and the source of power, means for normally maintaining the belt in engagement with the idle pulley, and means carried by the plunger coacting with said last named means for 65 throwing the belt in engagement with the fixed pulley, the means carried by the plunger serving to hold the belt upon the idle pulley during the period the plunger completes its return stroke and is initially on its 70 thrust stroke. 75

In testimony whereof I hereunto affix my signature in the presence of two witnesses.

GEORGE W. CAMERON.
